UNITED STATES PATENT OFFICE.

OSGOOD HILTON, OF SAN FRANCISCO, CALIFORNIA.

CHURN.

SPECIFICATION forming part of Letters Patent No. 360,299, dated March 29, 1887.

Application filed December 20, 1886. Serial No. 222,102. (No model.)

To all whom it may concern:

Be it known that I, OSGOOD HILTON, a citizen of the United States, residing at San Francisco, in the county of San Francisco and State 5 of California, have invented certain new and useful Improvements in Churns, of which the following is a specification, reference being had therein to the accompanying drawings.

My invention relates to certain new and useful improvements in churns; and it has reference particularly to that class known as "rotary double-dasher" churns.

This invention is designed, objectively, to improve the general construction of the class of 15 churns above mentioned, and provide a device that may be quickly and easily taken apart for cleaning or other purposes; and to this end it consists in the novel features of construction and arrangement of parts hereinafter set 20 forth and claimed.

In describing this invention reference is made to the accompanying drawings, in which Figure 1 represents a vertical sectional view of a churn, showing the dashers and operating 25 mechanism in side elevation; Fig. 2, a cross-sectional view of the main dasher; Fig. 3, a detail side elevation of the main dasher detached, and Fig. 4 a detail side elevation of the stock or shaft of the main dasher.

Referring to the annexed drawings by letter, A designates the body of the churn, which may be of any improved construction, and is provided with a cover, B, on which the operating mechanism is mounted, and which may be provided with a transparent window or peep-hole, as at C. Passing through a central aperture in the cover is a vertical rotating dasher-shaft, D, which is stepped at its lower end in a recess in the bottom of the churn, 30 and at its upper end in a bracket or standard, E, secured to the cover of the churn. Secured adjustably, by means of a set-screw, on the lower end of this shaft, inside of the churn-body, is a double dasher-blade, F, the two arms 35 of which are beveled or concaved in opposite directions, and are provided with short upwardly-extending dashers G, to aid in the churning process. Upon this shaft, near its upper end, is also secured a bevel-pinion, H, 45 which intermeshes with and receives motion

from a large bevel gear-wheel, I, on the end of the power-shaft, which is journaled in bearings in the brackets or standards E and J, and may be provided with a crank for operating it.

Set loosely on the vertical dasher-shaft, and supported and adjusted by means of the adjustable dasher-blade F, and fitting loosely and passing through the central aperture in the cover of the churn, is the main dasher K, having secured upon its upper end the bevel-pinion L, which also intermeshes with and receives motion from the large bevel-wheel I.

The shaft or stock L' of the dasher K is cylindrical at its upper end, and fits loosely in the central aperture in the churn-cover, and has its lower portion squared or made rectangular in cross-section and bifurcated, forming two depending wings or arms, L'', to embrace the body of the dasher-blades. This stock or shaft is provided with a vertical perforation 70 for the passage of the dasher-shaft, as shown.

Secured between the depending arms L'' of the stock L', and provided with vertical grooves for the reception of the said arms, is the body N of the dasher-blades O. The 75 blades O are made integral with and project laterally from each side of this body, the blades on one side being inclined in opposite directions from those on the other side, as clearly shown in the drawings, for the purpose of 80 thoroughly churning the cream contained in the churn-box. The body of the dasher-blades is also provided with a central aperture for the passage of the dasher-shaft, and the lower blades may be provided with short downwardly-projecting dashers P, similar to those 85 on the double dasher-blade F.

Interposed between the bearing-surfaces of the main dasher and the double dasher-blade F are the washers Q, for the purpose of preventing wear and friction of the parts.

As usual with this class of churning, the dashers, by reason of the disposition of the bevel-pinnions, are rotated in opposite directions during the operation of the churn.

It will be seen that by means of the adjustable dasher-blade F upon the shaft the main dasher is supported and adjusted to its place between the depending arms of the main stock, and by removing the blade F the main dasher-

blades may be slipped off the dasher-shaft, for renewal or cleaning.

Having thus fully described my invention, what I claim, and desire to secure by Letters 5 Patent, is—

In a churn, the combination, with the body and operating mechanism and the vertical dasher-shaft provided with a pinion, of the shaft or stock of the main dasher, provided 10 with a pinion and having a central perforation for the passage of the said vertical shaft and vertically bifurcated to form two depending arms, the vertically-perforated body of the

main dasher, provided with dasher-blades and vertically grooved on its outside for the reception of the depending arms of the main stock, and the adjustable double dasher-blade upon the vertical dasher-shaft, substantially as described.

In testimony whereof I affix my signature in 20 presence of two witnesses.

OSGOOD HILTON.
